UNITED STATES PATENT OFFICE.

LOUIS JACOBSON, OF PHILADELPHIA, PENNSYLVANIA.

DESIGN FOR A PAN FOR A LIGHTING FIXTURE.

Application filed May 4, 1921. Serial No. 466,699. Term of patent 3½ years.

To all whom it may concern:

Be it known that I, LOUIS JACOBSON, a citizen of the United States, residing at Philadelphia, in the county of Philadelphia and State of Pennsylvania, have invented a new, original, and ornamental Design for a Pan for a Lighting Fixture, of which the following is a specification, reference being had to the accompanying drawing.

Figure 1, is a side elevation of a pan for a lighting fixture, showing my new design.

Figure 2, is a similar fragmentary view at a slightly different angle; and

Figure 3, is a bottom view thereof.

1 designates the body of the pan, the same being of circular form and having on the periphery thereof at intervals, the outwardly projecting brackets 2.

Between the brackets are the panels 3 on the upper edge of opposite sides of each of which are the right lined horizontal portions 4, the concavities 5 on the inner terminals of the latter, and the right lined horizontal portions 6 elevated from the inner terminals of the concavities 5. 7 designates a convex crown which is surmounted on the inner terminals of the portions 6, and rise therefrom.

What I claim is—

The ornamental design for a pan for a lighting fixture as shown and described.

LOUIS JACOBSON.
